UNITED STATES PATENT OFFICE

EMIL H. GREIBACH, OF NEW YORK, N. Y., ASSIGNOR TO PACENT ELECTRIC COMPANY,
INC., OF NEW YORK, N. Y., A CORPORATION OF NEW YORK

PHOTO ELECTRIC SYSTEM

Application filed December 4, 1929. Serial No. 411,499.

This invention relates to photoelectric systems generally, but more particularly to apparatus of this sort as associated with sound film recording and projecting apparatus.

5 Special objects of the invention are to improve apparatus of this type in the matters of greater simplicity and ruggedness of mechanical construction; to make the apparatus in a form readily applicable to existing moving picture machines; to facilitate focusing and setting of the parts; to enable quick replacement of the excitor lamps and to increase the efficiency of the optical system.

10 Other objects and the novel features of construction, combinations and relations of parts by which the objects are attained will appear in the course of the following specification.

15 The drawings accompanying and forming part of this specification illustrate one of the practical commercial embodiments of the invention, but the invention is not limited to the details of construction illustrated, as will be clear from the broad scope of the patent 25 claims.

Figure 1 is a vertical sectional view of a form of the apparatus as it is applied to a standard motion picture projecting machine.

20 Figure 2 is a broken plan view of such a periscope.

Figure 3 is a broken part sectional and diaphragmatic view of the optical system.

Figure 4 is a detail view of the detachable periscope.

25 Figure 5 is a broken enlarged view of the optical "slit" and mask construction.

Figures 6 and 7 are sectional views of the same as taken on substantially the planes of lines 6—6 and 7—7 of Figure 5.

30 Figure 8 is a broken part sectional detail of the adjustable film guide roller.

Figure 9 is a sectional view of one of the interchangeable lamp holders with an excitor mounted therein.

35 Figure 10 is a plan view of the holder.

Figure 11 is a broken detail of the yielding film gate structure.

40 In Figures 1 and 2 the entire mechanism is shown as mounted in or supported by a casing 12, which may be attached by the bolts

13 to the base of a projecting machine in position to directly receive the film 14 from the projector through an opening 15 in the top of the casing.

The film from the projector passes first 45 over an idler guide roll 16, and thence through a film gate made up of the arcuate shoe 17, and cooperating edge retaining spring strips 18. This gate shoe has an exposure opening 19 in it, as shown in Figure 3. 50

The film is advanced down through the gate by a constantly running sprocket 20, suitably driven from the projector or synchronously therewith and is then advanced by sprocket 21 over guide roll 22 and out the 55 bottom of the casing through a roller passage 23. A guide is shown at 24 to strip the film from the teeth of sprocket 21 and insure its free passage on out of the machine.

The excitor lamp 25 is shown located in a 60 separate compartment at the back of the casing with its filament in line with the optical tube 26 and the photoelectric cell 27 is shown mounted in a separate compartment at the front of the casing in line with the optical 65 tube. These two compartments are preferably provided with readily removable covers 28, 29, enabling quick access to the lights.

It is important that there be no interruption through failure of the light source, and consequently, a special feature of the invention resides in the provision and mounting of extra light bulbs so that they may be quickly shifted one after the other into the optical axis. This is accomplished in the illustration by mounting the lamp bulbs in holders or bases 30 arranged to slide in a trackway 31 extending transversely of the optical axis. 75

In the construction here shown, the lamp bases 30 are made up as accurately machined metallic blocks grooved in their opposite sides at 32, to slidably engage ribs or rails 33 along opposite sides of the trackway, and carrying at the bottom, center contacts 34 mounted in insulation 35 and slidably projected by enclosed springs 36, Figure 9, which connect at the top with center contacts 37, slidably projecting through insulating discs 38 to engage the center lamp contacts 39. The lamp bases 40 are shown as having projecting 80

95

100

tabs 41 on opposite sides of the same, designed to enter through notches 42, Figure 10, in the overstanding confining flange 43. When so entered, the lamp bulbs are given a half turn to the position shown in Figure 9, where the mounting tabs or lugs 41 are fully engaged beneath the overstanding flange 43 and in such position, the lamps are held with the axis 44 of the filament in transverse alignment with the optical axis, as indicated in Figure 1. This method of mounting allows a certain "leeway" for turning the lamp to bring the filament in proper position, and the lugs are preferably made of relatively thin metal, as indicated, so that they will bend to enable the lamp being twisted one way or the other in its socket, space being provided at 45 (Figure 9) in the socket to allow a certain latitude of such twisting movement of the lamp base in the socket.

Located in the lamp trackway at a point to engage the bottom contact 34 of the socket when the lamp filament is alined with the optical axis, is an insulated current conducting contact spring 46, having a depression 47 as shown in Figure 1, to catch and hold the bottom contact when the socket is thus properly "centered".

As shown in Figure 2, the lamp track extends sufficiently to one or both sides of the optical axis to enable one or more extra lamp carrying sockets to be mounted alongside the active lamp, ready to be pushed over into the active contact making position the instant the lamp in use should fail. As a further precaution, extra lamp bulbs 25 may be mounted in spring brackets 48 on the back or cover compartment wall, ready to replace any burnt out lamps in the sliding sockets.

The optical tube is shown as adjustably and removably held by the bolts 49 in the split clamps 50, Figures 1 and 2. As shown in Figure 3, the optical system consists of the lenses 51, 52, arranged to condense the light from the excitor onto the opening 53 in the slit holder 54, so that the light passes in a narrowed beam from the slit 55 to the objective lens 56 in the forward end of the tube through the film slit 19 to the front lens 57, which condenses the projected light in the photoelectric cell.

The slit holder 54 is shown in the form of a sleeve set in the back end of the tube 26 against a shoulder 58 and alined by means of a pin 59 entering in a slot 60 in the side of the sleeve. The slit 55 is shown provided by co-operating slit plates 61, fastened on the sleeve over the large light opening 53 and formed with grooves 62 providing a slideway for the masks 63, Figures 5, 6 and 7. These masks are indicated as flat plates entered through a slot 64 in the side of the tube, these plates being slotted as at 65 to different lengths for the purpose of determining the effective

length of the light slit, as shown particularly in Figure 7.

The objective lens 56, Figure 3, is shown as carried by a lens holder 66, mounted in a ring 67 which screws into the end of the lens tube and in the illustration this ring is definitely located with respect to the end of the tube by means of a spacer ring 68 interposed between the mounting ring and the end of the tube. Spacer rings of different thicknesses may be employed to predetermine different positions of the objective lens and these spacer rings may be omitted to enable the mounting ring to come up against the end of the tube for another definite setting of the objective lens. The objective lens tube 66 is shown as entering a socket 69 in the back of the film guiding block 17, so as to confine and concentrate the light on the film passing over the guide.

The condensing lens 52, Figure 3, is shown as definitely positioned by bearing against the end of the slit ring 54 and the lens 51 is definitely positioned by bearing against a retaining ring 70 screwed on the end of the tube, the spring 71 placed between the lenses holding them against the positioning seats described.

The front condensing lens 57 is shown as definitely positioned by being forced by a spring 72, Figure 3, against an internal shoulder 73 in the sleeve 74, which is accurately positioned in the front wall of the casing, Figure 1, by having an external flange 75 bearing against the inner face of the wall and held so by a ring 76, screwed on the outer end of the sleeve and bearing against the outer face of the wall. This securing ring also serves as a retainer for the spring 72, the same being indicated as having an internal flange 77, serving as an abutment for the outer end of the spring.

For focusing purposes, a "periscope" may be employed and a special feature of the same is that this periscope is readily removable from the optical system. For the purpose the lens tube is provided with an opening 78 in the outer side of the same, Figure 2, into which the inner end of the periscope tube 79 fits, the latter having a pin 80 on the inner end of the same to enter a notch 81 in the edge of the periscope opening to interlock the periscope in proper position with the prism 82 properly disposed in the optical axis. This prism is shown as mounted in an open setting 83 supported at the inner end of the periscope tube. When the periscope is removed, the opening in the side of the lens tube may be closed by turning the cover sleeve 84 over the same, said sleeve being shown in Figure 2 as having an opening 85 to uncover the periscope opening when alined therewith.

The film gate strips 18 are shown in Figures 1 and 11 as carried by a lever 86 pivoted

at 87 and tensioned by a spring 88 toward the stationary film guiding support 17. A cam or eccentric 89 is shown mounted on this lever in position to engage a shoulder 90 on the frame or casing and this eccentric is shown as adapted to be turned by a handle 91 so as to force the gate lever back from the stationary film support, as in Figure 11, or to let the spring 88 thrust the lever over so that the strips 18 are tensioned against the film, as in Figure 1.

The film guiding roll 16, Figures 1, 2 and 8, is illustrated as laterally adjustable for accurately directing the film to the film gate 15 by means of a bearing screw 92, thrusting the roll over against the tension of a spring 93 and secured in adjusted relation by lock nut 94.

As clearly shown in Figures 1, 2 and 8, the optical tube and associated film guiding means are all mounted on a single bracket 95, detachably fastened in place on the inner side wall of the casing by screws 96, so that in case of need, these associated parts may be 25 taken out as a unit without disturbing their associated relations.

If desired, all electrical connections to the apparatus may be made by a single multi-pronged plug, such as shown at 97 in Figure 30 1, designed to fit a corresponding socket or terminal block suitably mounted on the apparatus.

The film advancing portion of the apparatus may be suitably driven from the moving picture machine, or be independently 35 driven, as desired. The optical tube may be readily adjusted in the supporting clamp structure provided therefor or be entirely removed therefrom. The main compartment 40 of the machine is shown in Figure 2 as having a hinged door 98 to provide ready access to the optical system and associated parts. As appears particularly in Figure 3, the light is "flooded" in a relatively wide beam through 45 the aperture 53 onto the slit 55, so that no difficult focusing is involved, and so that the light issuing through the slit is uniform in its cross sectional outline. The masks are readily interchangeable to vary the length 50 of the slot. The periscope similarly is readily removable, is out of the way when not required and at the same time can be quickly applied when needed.

If the lamp burns out, there need be 55 practically no interruption in the operation as it is only necessary to push the spare lamp over in place of the burned out lamp, this being a simple, positive operation by means of the coaction between the bottom contact on 60 the lamp socket with the current conducting contact spring which holds the socket in position with the lamp filament lined up with the optical axis. The defective lamp may be replaced by one of the extra lamps 65 and a "spare" be thus provided, ready to be

shifted back into alignment with the optical axis if the second lamp should fail for any reason.

The film guiding spool 16 is illustrated as made up of two end spool sections 99, 100, 70 Figures 2 and 8, with a spring 101 on the shaft of the spool, and forcing the two end heads together against an abutment shoulder 102. This construction enables the heads of the spool to yieldingly grip the edges of the film, confining and directing it accurately to the film gate. The abutment 102 is indicated as a stop collar adjustably secured on the shaft by a screw 103 to form a fixed abutment for definitely positioning the sound record edge of the film with respect to the optical system. By this means the sound track can be brought into absolute register with the optical axis and in any adjusted position, the film will be properly gripped at the edges by means of the spring take-up on the spool head.

The periscope can only be mounted on the lens tube and used when the door of the casing is open, as will be clear from Figure 2, and this relation constitutes a safety measure, insuring the removal of the periscope before the machine is operated.

What is claimed is:

1. In apparatus of the character disclosed, 95 the combination of an optical system, an excitor lamp at one end of the same and a photoelectric cell at the opposite end, a socket for said excitor lamp and a trackway for mounting said socket in transversely movable relation at the end of the optical system, enabling the replacement of one lamp for another by the transverse shifting of a lamp carrying socket in the trackway aforesaid. 100

2. In apparatus of the character disclosed, 105 the combination of an optical system, an excitor lamp at one end of the same and a photoelectric cell at the opposite end, a socket for said excitor lamp, a trackway for mounting said socket in transversely movable relation at the end of the optical system, enabling the replacement of one lamp for another by the transverse shifting of a lamp carrying socket in the trackway aforesaid, a current conducting lamp-engaging contact on the socket and current conducting contacts on the socket and trackway cooperating in the position of alignment of the lamp with the optical axis. 110

3. In apparatus of the character disclosed, 120 the combination of an optical system, an excitor lamp at one end of the same and a photoelectric cell at the opposite end, a socket for said excitor lamp and a trackway for mounting said socket in transversely movable relation at the end of the optical system, enabling the replacement of one lamp for another by the transverse shifting of a lamp carrying socket in the trackway aforesaid, 125 said trackway being of sufficient transverse 130

- extent to support a number of lamp sockets aligned in readiness, one to be shifted in place of the other.
4. In apparatus of the character disclosed, 5 a lens tube having an opening in one side of the same, a periscope detachably engageable in said opening and a cover for said tube opening for closing the same when the periscope is removed.
- 10 5. In apparatus of the character disclosed, a lens tube having an opening in one side of the same, a detachable periscope, means for removably supporting said periscope in definitely related position over said opening in 15 the lens tube and means for covering the opening in the tube when said periscope is removed.
- 20 6. In apparatus of the character disclosed, the combination of a lens tube, a lens holder removably and adjustably engaged with one end of the tube and an annular spacing member carried by said lens holder for definitely positioning the same relative to the end of the lens tube.
- 25 7. In apparatus of the character disclosed, a slit holder having a wide slot, slit members carried by said holder and cooperating to form a narrow slot in line with the wide slot of the holder, said slit members having 30 cooperating parts providing a guideway for a slit-length determining mask.
- 35 8. In apparatus of the character disclosed, a slit holder having a wide slot, slit members carried by said holder and cooperating to form a narrow slot in line with the wide slot of the holder, said slit members having 40 cooperating parts providing a guideway for a slit-length determining mask, a lens tube in which the slit holder is mounted, said lens tube having a slot in one side of the same in line with the guideway of the slit members and a mask plate insertable through the slot into said guideway.
- 45 9. In apparatus of the character disclosed, the combination with an optical system of an excitor lamp having bendable supporting tabs at opposite sides of the base of the same and a socket freely receiving the base of the lamp, said socket having means for holding 50 said bendable tabs and the base of the lamp being shiftable in the socket when the tabs are bent to hold the lamp in different positions and means for supporting the socket with the lamp adjusted therein in alignment with the axis of the optical system.
- 55 10. In combination with a lens tube, an excitor lamp having bendable tabs projecting from opposite sides of the base of the lamp, a socket for holding said tabs in a definite 60 position, said lamp being shiftable with respect to the socket in the bending action of the tabs when the latter are held in the socket, means for supporting the socket with the lamp carried thereby aligned with the 65 optical axis of the lens tube.
11. In combination with a lens tube, an excitor lamp having bendable tabs projecting from opposite sides of the base of the lamp, a socket for holding said tabs in a definite 70 position, said lamp being shiftable with respect to the socket in the bending action of the tabs when the latter are held in the socket and spring pressed contact means carried by the socket and operative in all adjusted positions of the lamp in the socket, 75 means for supporting the socket with the lamp carried thereby aligned with the optical axis of the lens tube.
12. In apparatus of the character disclosed, a lens tube, an excitor lamp socket having grooves in opposite sides of the same, a spring terminal contact in the bottom of the socket, a trackway for the socket having flanges engaged in the grooves in the socket and a contact terminal between the track flanges co-operating with the spring contact of the socket for yieldingly retaining the socket in definite position in the trackway in line with the lens tube.
13. In apparatus of the character disclosed, 90 the combination of a casing having a door providing access to the interior of the same, an optical system including a lens tube, within the casing and a periscope removably attachable to the lens tube when said door is open, said door being closable only when the removable periscope is detached from the lens tube.
14. In apparatus of the character disclosed, 95 the combination of a lens tube, a lamp holder, an excitor lamp universally adjustable in said holder and having means cooperating with the holder for releasably retaining said lamp in its universally adjusted relation in the holder and means for supporting and retaining said holder in predetermined definite relation to the lens tube.
15. In apparatus of the character disclosed, 100 the combination of an excitor lamp, a holder for said lamp, said lamp having a universally 110 adjustable mounting in said holder and co-operating means on the lamp and holder for releasably retaining the lamp in universally adjusted relation in the holder and a support having means for positioning and retaining the holder in predetermined relation.
- In testimony whereof I affix my signature.
- EMIL H. GREIBACH.
